SOFA

Hubert Howard Watson and Mike Stewart Watson, Galax,
Va., assignors to Sawyers Furniture Company, Galax,
Va.

Filed July 31, 1969, Ser. No. 18,481

Term of patent 14 years

Int. Cl. D6—01

U.S. Cl. D15—11

FIG. 1 is a perspective view of a sofa showing our new design;

FIG. 2 is an end elevational view of the sofa; and
FIG. 3 is an enlarged fragmentary view showing the lower right front corner of the sofa in greater detail.

The end of the sofa not shown is a mirror image of the end shown while the back of the sofa is conventional.

We claim:

The ornamental design for a sofa, as shown and described.
